ELMER E. SPEER, OF BALLSTON, VIRGINIA.

BINDING DEVICE FOR MOLDS, ETC.

Application filed February 15, 1926. Serial No. 88,418.

My invention relates to binding devices for reinforcing molds or forms used in concrete construction work and more especially to the provision of a clamp for use in tightening the binding straps around the mold and firmly connecting the ends thereof together to provide a rigid structure; the present invention being an improvement upon the clamping device shown in my prior

10 Patent No. 1,268,061, dated May 28, 1918.

In the device shown in the patent the flanged plate or keeper of the clamp is provided with a cam at each end for connecting the ends of the metal strap which is bound around the mold and although this arrangement possesses certain advantages, particularly when it is desired to draw upon both ends of the strap successively in tightening the same around the mold, I have found 20 that in many instances the strap or band can be drawn tightly by drawing upon one end only and although this operation was contemplated in my prior patent I have discovered that the clamping device can be 25 simplified and manufactured more economically by employing the improved means, herein disclosed, for connecting one end of the metal strap or band to the base-plate of the clamp, and, furthermore, that the form 30 of cam used in the present instance for gripping the other end of the metal strap or band will facilitate the operation thereof; these improvements also permitting a reduction 35 in the length of the base-plate.

With these principal objects in view my present invention consists in the particular construction of the clamp or device for tightening and securing the ends of a binding strap around a mold or other object to 40 be reinforced in this manner; all as herein-after fully described and set forth in the appended claims.

In the accompanying drawings:

Figure 1 is a side elevation showing the 45 application of my invention to a mold or form for constructing a concrete column.

Fig. 2 is a longitudinal sectional view of the clamp, enlarged, showing the ends of the binding strap secured thereto.

Fig. 3 is a detail side elevation of the 50 clamp.

Fig. 4 is a plan view thereof, and

Fig. 5 is a side view illustrating the operation of tightening the strap or band with a pulling implement which cooperates with 55 the clamping device.

The main part of the metal clamping device is preferably formed by casting to provide a base-plate 10 with ears 11 11 at one end thereof to receive a cam 12 between 60 them, and ears 14 14 at the other end to receive a pulling implement, such as herein-after described, for drawing on one end of the binding strap or band; said pairs of ears rising from the base-plate at opposite side 65 edges thereof. The ears 11 are pierced to receive a pintle 13 on which the cam 12 is mounted, and the ears 14 are provided with recesses 16 opening out at the upper end thereof, said recesses being rounded at 70 their lower ends to form seats in which the pulling implement is fulcrumed. In the present instance a transverse slot 17 is formed in the base-plate near the end thereof opposite the cam for connecting one end of the 75 metal binding strap or band 15 to the clamp, the length and width of said slot being such as to receive an end portion of the strap bent upon itself as shown in dotted lines Fig. 2, whereby when the looped end 15a— 80 passed upward through the slot—is flattened upon the base-plate and the portions of the strap below the latter are bent in opposite directions against the underside thereof, as shown in full lines, this end of the metal 85 strap will be securely connected to the clamping device.

The ends of the pintle 13 upon which the cam 12 is mounted and which pass through the ears 11 are upset at the outer side of said 90 ears for permanently connecting the parts together, and in the present instance the cam is operated to clamp the metal strap 15 against the base-plate by means of a shank 18 projecting upwardly therefrom at right 95 angles to its axis, whereby instead of turning the cam by means of a wrench as provided for in the construction shown in my

prior patent it is turned by simply striking the projection or shank with a hammer, and it will be obvious that this arrangement not only facilitates the operation but permits the cam to be driven tighter against the band in clamping it against the base-plate.

Although any approved type of pulling implement may be employed for tightening the metal strap 15 around the mold I have illustrated a preferred form consisting of two parts or members pivoted together, one being a block 20 having trunnions 22 at its lower end by which it is fulcrumed between the ears 14 of the clamp hereinbefore described and provided with upwardly projecting spaced apart arms or plates 23, and the other a lever 21 pivoted between the arms or plates on a transverse pin 24; the inner end of the lever cooperating with the block 20 in clamping the metal strap between them. The surface of the block between the ears, over which the metal strap passes, is eccentric to the axis of the block and the swinging movement of the lever between the ears or plates is limited in one direction by contact with said surface and in the other direction by a pin 25 projecting from the lever engaging a stop-shoulder 26 formed at the upper end of one of the plates.

In tightening a metal band around an object to be reinforced, for instance a form for molding a concrete column as shown in the drawings comprising a box A with beveled-end battens B at the four sides thereof, one end of the metal band is connected to the clamping device by means of the slot 17 in the manner hereinbefore described and after passing said band around the mold or battens B the other end thereof is threaded 40 between the cam 12 and base-plate and drawn tight by the pulling implement mounted between the ears 14 as shown in Fig. 5. When the band is drawn tightly around the mold the end thereof which passes below the cam to the pulling implement is secured to the clamping device by turning the cam against the same to clamp this end of the metal band against the base-plate. The pulling implement is then removed for use in applying other metal straps or bands around the mold, it being understood of course that a clamping device is used in the operation of applying and securing each reinforcing band that is employed in binding the mold.

In attaching one end of the binding strap to the clamping device through the medium of the slot 17 I have found it more convenient to flatten out the loop 15^a in a vise before passing the strap through said slot, and of course in this instance the other end of the strap would be passed downward through the slot and drawn through until the flattened loop rested on the base-plate, after which the terminal of the strap is bent inward

against the base-plate and the body portion of said strap bent outward against the base-plate, being held firmly against the mold when the strap is bound tightly around the same, that is to say the portions of the metal strap lying against the underside of the base-plate are clamped against the mold and insure a firm connection which will withstand the pulling strain on the strap tightened around the mold.

The device hereinbefore described not only facilitates the operation of applying a metal strap around a mold for reinforcing the same but also connects the ends of the strap in such manner as to not injure the same, whereby the metal strap with clamping device attached may be used a number of times. Of course it will be understood that the binding device may be used in other situations or wherever it is desired to reinforce a structure, and that instead of using a flat strip of metal around the mold or other structure a length of wire of suitable gauge may be employed.

I claim:—

1. A device for connecting the ends of a metal strap around a mold comprising a base-plate having a narrow slot therein through which a looped end of the strap is passed and flattened on said base-plate for connecting it thereto, and a cam pivoted between ears on the base-plate and cooperating therewith for securing the other end of the strap to the device.

2. A device for connecting the ends of a metal strap around a mold comprising a base-plate having a narrow slot therein through which a looped end of the strap is passed and flattened on said base-plate for connecting it thereto, a cam pivoted between ears on the base-plate to cooperate therewith in securing the other end of the strap to the device, and a stout lug projecting from the periphery of said cam providing means for turning the same.

3. A device for binding molds comprising a base-plate having a slot therein to receive one end of a metal strap, and a cam pivoted between ears on the plate to cooperate therewith for connecting the other end of the strap thereto; together with a metal strap bent upon itself to provide a loop the outer portion of which is threaded through the slot in the base-plate and flattened on the base-plate.

4. A device for binding molds comprising a base-plate having at one end a pair of ears forming bearings for a pulling implement and a narrow slot in said base-plate for connecting one end of a metal strap thereto, the other end of said base-plate having a pair of ears and a cam pivoted between said ears to cooperate with the base plate for securing the other end of the metal strap thereto.

5. A device for binding a metal strap around a mold comprising a base-plate having a pair of ears at one end with recesses in the upper ends of said ears providing seats for a pulling instrument, a narrow transverse slot at this end of the base-plate through which an end of the metal strap is looped and flattened on said base-plate, a pair of ears at the other end of the base-plate, a cam mounted in and between said ears to cooperate with the base-plate for securing the other end of the metal strap to the device, and a stout lug projecting from the periphery of the cam providing the means for turning the same. ¹⁰
